(57) **CLAIM**

The ornamental design for an interlocking fastener, as shown and described.

DESCRIPTION

FIG. 1 is a rear isometric view of a first embodiment of a new ornamental design for an interlocking fastener, and showing the novel design.

FIG. 2 is a front isometric view of the first embodiment of the new ornamental design for the interlocking fastener, and showing the novel design.

FIG. 3 is a front view of the first embodiment of the new ornamental design for the interlocking fastener, and showing the novel design.

FIG. 4 is a rear view of the first embodiment of the new ornamental design for the interlocking fastener, and showing the novel design.

FIG. 5 is a right side view of the first embodiment of the new ornamental design for the interlocking fastener, and showing the novel design.

FIG. 6 is a left side view of the first embodiment of the new ornamental design for the interlocking fastener, and showing the novel design.

FIG. 7 is a top view of the first embodiment of the new ornamental design for the interlocking fastener, and showing the novel design.

FIG. 8 is a bottom view of the first embodiment of the new ornamental design for the interlocking fastener, and showing the novel design.

FIG. 9 is an environmental front view of the first embodiment of the new ornamental design for the interlocking fastener, illustrating two interlocking fasteners interlocked. FIG. 10 is an environmental isometric view of the first embodiment of the new ornamental design for the interlocking fastener, illustrating two interlocking fasteners interlocked; and,

FIG. 11 is a rear view of a second embodiment of the new ornamental design for the interlocking fastener, wherein the second embodiment of the interlocking fastener is simply thinner but holds all the other physical aspects of the interlocking fastener of the first embodiment.

The shade lines in the Figures (FIGS. 1-11) show contour and not surface ornamentation.

The broken lines rendered in FIGS. 9 and 10 illustrates the environment of the claimed design and forms no part thereof.
